CHOCK FOR A BOAT CLEAT OR THE LIKE

Donald J. Behnk, Pittsburgh, Pa., assignor to Attwood Brass Works, Inc., Grand Rapids, Mich., a corporation of Michigan

Application May 14, 1958, Serial No. 50,879

Term of patent 14 years

(Cl. D71—1)

Fig. 1

Fig. 2

Fig. 3

Fig. 4

Fig. 1 is a perspective view of a chock for a boat cleat or the like showing my new design;

Fig. 2 is a top plan view thereof; and

Fig. 3 and Fig. 4 are front and side elevational views, respectively, thereof.

I claim:

The ornamental design for a chock for a boat cleat or the like, substantially as shown.
